UNITED STATES PATENT OFFICE.

KARL MENSING, OF HANAU, GERMANY, ASSIGNOR TO GENERAL ELECTRIC COMPANY,
A CORPORATION OF NEW YORK.

GAS-TIGHT SEAL.

1,141,133.

Specification of Letters Patent.

Patented June 1, 1915.

Application filed October 30, 1913. Serial No. 798,248.

To all whom it may concern:

Be it known that I, KARL MENSING, a subject of the Emperor of Germany, residing at Hanau-on-the-Main, Germany, have invented certain new and useful Improvements in Gas-Tight Seals, of which the following is a specification.

The present invention comprises a gas-tight seal for envelopes in which for any reason a seal made by fusion is not practicable. For example, in the utilization of silica for electrical apparatus, mechanically fitted leading-in conductors are commonly employed, because of the high fusing point and low thermal expansion coefficient of silica. In order to maintain such seals perfectly gas-tight, ante-chambers filled with mercury have been placed around the exterior of the closure, but such seals are still accompanied by the disadvantage that tilting or inverting the device is apt to bring into direct contact with the mechanical seal a bubble of gas which in course of time accumulates in the ante-chamber, and thus permits gas to penetrate into the main container.

In accordance with my invention I provide an ante-chamber filled with mercury, or other sealing liquid, the chamber being so constructed and the seal being so located therein, that a space or pocket is provided above the exposed end of the seal in any position of the device, so that a gas bubble will rise above the exposed end of seal and in no case comes in contact with the closure even when the device is inverted.

My invention will be pointed out with greater particularity in the appended claims.

40 In the accompanying drawing, Figure 1 is a sectional view illustrating somewhat diagrammatically my novel construction; Figs. 2 and 3 illustrate the same construction in different positions; and Fig. 4 illustrates a modification.

Referring to Fig. 1 the main envelop 1 may consist, for example, of material such as fused quartz as commonly used for vapor electric devices. All the parts of the vapor electric device itself have not been shown as these are well understood in the art and form no part of the present invention. Into the mouth or nipple part 9 of the receptacle is fitted or embedded a plug 2 consisting of 55 material having practically the same coeffi-

cient of expansion as the wall. For example, in the case of a quartz receptacle the plug may consist of nickel steel. This plug may be tapered as shown in the drawing. Adjoining the plug 2 is a receptacle 3 which 60 constitutes an ante-chamber and which contains a quantity of mercury, or other heavy liquid 4, for the purpose of sealing the joint between the plug 2 and the wall of the envelop 1. As indicated, this chamber is provided with an annular pocket 5 surrounding but out of immediate contact with the plug 2. The receptacle 3 is provided with an exterior closure or plug 6 also of nickel steel. The walls of the chamber 3 are preferably 65 bulged outwardly, as indicated. It will be observed that this construction locates the exposed joint between the plug 2 and the adjoining wall practically in the center of the mercury filled chamber. If a small 70 amount of gas slowly leaks by the plug 6 it will not come in contact with the inner plug 2 when the device is tilted. As shown in Fig. 2, space for it is provided by the convexity of the walls and when the device is 75 inverted space is provided for the gas by the annular pocket 5, as shown in Fig. 3, so that in all cases the joint between the inner plug 2 and the projecting mouth 9 of the device is covered by sealing liquid. 80

85 In the construction shown in Fig. 4 the closures 7 and 8 are screw-threaded into the wall 1, and any other means of making a joint mechanically as tight as possible may be used. In fact, in some cases this construction will be found to be useful where the materials constituting the walls of the vessels are fused about the leading-in conductor and for any reason a vacuum or gas-tight seal cannot be obtained by this method 90 alone. For example, when the chemical nature of either the wall or the sealing-in material is such that proper adhesion does not take place between the two. Not only may such seals be used to advantage in vessels 95 consisting of refractory material such as quartz, but also metal such as iron in which mechanically fitted seals are necessary.

What I claim as new and desire to secure by Letters Patent of the United States, is:— 105

1. The combination of an envelop having a projecting mouth, a mechanically fitted closure therefor, a receptacle surrounding said projecting mouth, a sealing liquid in said receptacle, the shape of said receptacle 110

and the amount of the sealing liquid being adapted to cover with said liquid the joint between the walls of the envelop and the mechanically fitted closure in all positions 5 of said envelop and an external closure for said receptacle.

2. In an electrical apparatus, an envelop having a projecting mouth, a fitted electrically conducting closure therefor, a receptacle surrounding said closure, a conducting liquid partly filling said receptacle sufficient in amount to cover the joint between said closure and the adjacent wall of the envelop in all positions of the apparatus, and an 10 external conducting closure for said receptacle.

3. In an electrical apparatus, an evacuated envelop, and current-conveying means therefor comprising a solid conductor embedded in an outwardly projecting section 20 of said envelop, a receptacle surrounding said projecting section and said conductor, said receptacle having a pocket adjoining

the section into which said conductor is sealed to provide space for a gas bubble out 25 of contact with the exposed end of the conductor, a quantity of mercury in said envelop proportioned to cover the joint between said conductor and the adjacent wall in all positions of said envelop, and a conducting closure for said receptacle.

4. The combination of a gas-tight envelop, a mechanically fitted closure in the wall of said envelop, a receptacle surrounding the external end of said closure, a body of mercury in said receptacle, the end of said closure projecting with a surrounding wall 35 into said receptacle so that it will be immersed in mercury even when inverted, and an external closure for said receptacle. 40

In witness whereof, I have hereunto set my hand this 17th day of July, 1913.

KARL MENZING.
